Primary Examiner — Sandra Snapp*Assistant Examiner* — Altaira J Swangin(74) *Attorney, Agent, or Firm* — Raymond Y Chan; David and Raymond Patent Firm(57) **CLAIM**

The ornamental design for a keyboard, as shown and described.

DESCRIPTION

FIG. 1 is a perspective view of the keyboard showing my new design.

FIG. 2 is a front view of the keyboard.

FIG. 3 is a left side view of the keyboard.

FIG. 4 is a rear view of the keyboard.

FIG. 5 is a right side view of the keyboard.

FIG. 6 is a top view of the keyboard; and,

FIG. 7 is a bottom view of the keyboard.

The broken lines shown in the drawings depict portions of the keyboard and form no part of the claimed design.

1 Claim, 7 Drawing Sheets(56)
